UNITED STATES PATENT OFFICE.

GEORGE P. BRAND, OF NEW YORK, N. Y.

SHEET-CENTRALIZING MECHANISM.

1,219,235.

Specification of Letters Patent. Patented Mar. 13, 1917.

Application filed April 12, 1915. Serial No. 21,166.

To all whom it may concern:

Be it known that I, GEORGE P. BRAND, a citizen of the United States, residing at New York, in the county of New York and State of New York, have invented certain new and useful Improvements in Sheet-Centralizing Mechanism, of which the following is a specification.

This invention relates to certain new and useful improvements in centralizing devices 10 for movable webs such as note sheets of musical instruments, automatic typewriting machines and the like.

The present invention has for its object 15 among others to provide a simple and efficient centralizing device for automatically accurately contralizing webs of different widths.

Within the music spool box I mount near 20 each end of the trackerbar a pneumatic, each pneumatic having a port controlled by a valve carried by the pneumatic and coöperating with means coacting with the edges of a note sheet. These parts are reduced to 25 a minimum and being within the music spool box are less liable to injury and are out of the way. The pneumatics are connected by means within the music spool box so as to move in unison and insure utmost 30 accuracy. By this arrangement climatic conditions have minimum effect upon the result attained. At the back of the music spool box I arrange the pneumatics of the music spool centralizing mechanism, thus 35 economizing space and placing the pneumatics in position where they are not visible to the eye of the operator.

I connect the end spindles of the music spool by means controlled by the pneumatics at the rear of the music spool box 40 just referred to.

Other objects and advantages of the invention will hereinafter appear and the novel features thereof will be particularly 45 pointed out in the appended claims.

The invention is clearly illustrated in the accompanying drawings, which, with the numerals of reference marked thereon, form a part of this specification, and in which— 50 Figure 1 is a top plan with a portion removed showing my present improvement.

Fig. 2 is a front elevation thereof.

Fig. 3 is a rear elevation.

Fig. 4 is a detail in end elevation.

55 Fig. 5 is a detail in elevation looking at the opposite end from that seen in Fig. 4.

Fig. 6 is a diagrammatic view of the pneumatic elements and connections.

Fig. 7 is an enlarged sectional view of the bleed device shown in Fig. 6 intermediate the pneumatics.

Fig. 8 is an enlarged perspective view of one of the levers of the edge guide mechanism.

Fig. 9 is a longitudinal section through the lever seen in Fig. 8 with its connected member in position.

Fig. 10 shows a perspective detail of the adjacent ends of the members connecting the pneumatics within the music spool box.

Fig. 11 is an edge view of the connecting means and pneumatics which they connect, with the connecting means shown in section.

Fig. 12 is an enlarged section as on the line 12—12 of Fig. 6.

Like numerals of reference indicate like parts throughout the several views.

In the drawings I have chosen to show only such parts of a mechanical musical instrument as are intimately associated with my present invention, it being understood that the parts not herein shown or described may be of any well known or approved form of construction.

1 designates the music spool box, 2 a trackerbar, 3 the take-up spool and 4, 4 the spindles on which the music spool is designed to be mounted for rotation. In use the trackerbar is relatively fixed.

Within the box 1 and preferably beneath the trackerbar, I arrange pneumatics 5, 5, one near each end of the trackerbar and secured to or within the box in any suitable manner. As seen best in Fig. 12, the movable board or member 6 of each pneumatic 5 is provided with a port 7 which is controlled by a valve 8 movably secured at one end, as at 9, in any suitable manner, as by the leather facing of said valve to the movable member 6, so as to control said opening, a spring 10 in this instance shown as surrounding a screw or the like 11 held in the movable member 6 and loosely movable through an opening in the valve and the spring being seated at one end in a depression or cavity 12 in the valve and rendered adjustable by a nut or the like 13 on the end of the screw, serves to normally seat the valve. These pneumatics are fixed relatively to the trackerbar and are connected by means to insure that they shall move in unison with the greatest accuracy. In the

present instance, I have shown them as connected in the following manner: 14 are connectors preferably, though not necessarily, of aluminum, secured each at one end, as at 15, to a movable member 6 of a pneumatic 5. The other ends of these connectors 14 are overlapped, as seen in Fig. 11, the end of one being provided with an elongated slot 16 and the other with a pin 17 or projection or the like 17 which works in said slot as the pneumatics move to permit of the necessary longitudinal play. By this means movement of one pneumatic necessarily will give movement to the other, so that the two pneumatics move in perfect unison.

As the mechanism is the same at both ends of the box, so far as pertains to the pneumatics 5 and their closely associated parts, a description of one will suffice for both. Referring, therefore, to Figs. 1 and 2, 18 is a rod mounted to slide freely in an opening in the end of the box 1 and may be guided in a tube 19, as shown. 20 is a resilient button or the like on the outer end of the rod 18 designed for contact with one end of a member 21 pivotally mounted, as at 22, on a rod or the like 23 fixed in the end of the box 1 and projecting outward beyond the same. The other end of this lever 21 is designed for contact with a resilient button or the like 24 carried on a rod 25 movable through an opening in the end wall of the box 1 and which may be guided through a tube 26, as shown. 27 is a spring around the tube 26 between the button 24 and the adjacent face of the end wall of the box 1. The inner end of the rod 25 carries a member 28 adapted for contact with the edge of a note sheet. The lever 21 may be pivotally mounted in any suitable manner, but in the present instance is shown as provided with ears 29, see Figs. 8 and 9, having openings 30 for the passage of the pivot 22, the rod 23 working through a slot 31 in the body portion of said lever.

At each end of the back of the box 1 I mount a pneumatic 32 secured thereto in any suitable manner and each connected 50 with the adjacent pneumatic 5 by a tube or conduit 33, as seen best in Fig. 6.

Each pneumatic 5 is further connected by a tube or conduit 34, 35, with bleed chambers in a box 36, all as seen in Fig. 6. Referring to Fig. 7, it will be seen that the box is mounted on a coupling board 37, as will be seen also in Fig. 4. This box has a bleed chamber 38 with which the conduit 34 connects through the passage 39 in said 60 box and a chamber 40 with which the conduit 35 connects through a passage 41. 42 is a tube for supplying tension. It is designed to be connected with the wind chest or action chest, not shown, or any other 65 source of supply for the operation of the

device. It communicates with a passage 43 in the coupling board, as seen in Fig. 7, and from this passage 43 are bled 44 and 45 into the chambers 40 and 38 respectively.

As seen best in Fig. 6, each pneumatic 5 is provided with a spring 46 tending to normally keep the pneumatic in its inflated condition.

As seen best in Fig. 1, each pneumatic has attached to the movable member thereof an arm 47 with a substantially right-angled extension 48, to the free end of which is pivotally connected one end of a rod 49, the other end of which is adjustably connected by buttons or the like 50 with an arm 51 rigidly secured to a depending portion 52 of a U-shaped member 53. 54 is another U-shaped member rigid with the U-shaped member 53 and having the depending portions 55, as seen best in Fig. 2. 56 are uprights having the transverse lower portions 57 which are loosely secured to the ends of the music box 1 by any suitable means, as the screws or the like 58, so as to permit of bodily movement of the uprights 56 which serve to support the U-shaped members just described.

The spindles 4 for the music spool are endwise movable through the uprights 56 and the ends of the box 1 and move with the U-shaped bars 53 and 54.

The uprights 56 are held against displacement by pins or the like 59, see Fig. 2, which form a loose connection between said uprights and the adjacent U-shaped bar 54.

The U-shaped bars 53 and 54 and their connections and supports constitute what I term a floating transmission device, but no claim *per se* is made thereto in this application as the same will form the basis of a separate application. It is herein shown, however, as one form of mechanism for cooperation with the edge guide mechanism hereinbefore described in detail.

In connection with the mechanism hereinbefore described, I may employ a pneumatic brake, one form of which is herein shown and comprises a pneumatic 60 mounted upon and adapted to move with the floating transmission members above described. The brake member 61 is connected with and actuated by the movable member of the pneumatic 60 and acts against the periphery of the wheel 62 on the shaft 63 of one of the spindles 4 of the music roll, as seen in Fig. 5. No claim, however, is made in this application to this brake mechanism.

64 is a connection leading from the pneumatic 60 to the action chest, not shown, in a manner usual and well known in this class of devices. The springs 10 are of sufficient strength to overcome the springs 27 at the proper time.

With the parts constructed and arranged

substantially as hereinbefore described, the operation will be as follows:—

The floating transmission device seen best in Fig. 2 and with which the music spool spindles 4 are movable, operates as follows:—The pneumatics 32 situated at the back of the box on each end are connected to the transmission to cause it to move to the right and left. When the pneumatic 32 on the left is wholly or in part collapsed, it carries the transmission to the left and forces the pneumatic 32 at the right to open and when the pneumatic 32 is wholly or in part collapsed it has the opposite effect on the pneumatic 32 at the left of the box. Thereby, it is readily seen that the transmission is carried either to the right or the left by the pneumatics 32.

When a roll is inserted in the usual manner, the edge guides are normally out of contact with the note sheet, as seen in Fig. 2 in full lines. This is done for the purpose of admitting sheets of greater width and also insuring that the edge guides shall be out of contact with the sheet when rewinding the music. It is constructed also to take in sheets of much less width than shown in Fig. 2, as no operation takes place until the pneumatics 5 collapse, forcing the edge guides against the edges of the sheet, as shown in dotted lines in Fig. 2, whether it be of less or greater width. If one edge guide hits the sheet first and the sheet not being central, that particular edge guide (for illustration the edge guide on the right side of the sheet) will cause the valve 8 to open, letting air through the port 7 into the pneumatic 5, admitting air into pneumatic 32 through the connections from the pneumatic 5 to the pneumatic 32, inflating the pneumatic 32, at the same time weakening the pressure of the bleed chamber 40, at the same time the valve 8 on the opposite side of the sheet is closed to the atmosphere, allowing the bleed 44 in the bleed chamber 40, through the connections 35 and 33, to draw air from the pneumatic 5 and 32 on the opposite side, causing the pneumatic 32 and pneumatic 5, to collapse until the sheet is drawn to the left until both edge guides are in contact with the sheet at the same time. Then, the bleeds in the bleed chambers 40 and 38 are constantly drawing on their respective pneumatics. Consequently, when the two edge guides strike the sheet at the same time, both valves 8 are opened just a little, enough to allow atmosphere to enter each port 7 in the pneumatics 5, through the connections into the respective bleed chambers, overcoming the bleeds 44 and 45, thereby putting the sheet in a central position. Now, this mechanism being so constructed that when the slightest movement possible in either direction of the sheet takes place, it gives a double movement in the operation of

the two valves 8 on the pneumatics 5, for instance, if a sheet should start to move to the left in the smallest degree, the valve 8 on the pneumatic 5 at the right will close and cause the said pneumatic to start to collapse and at the same time preventing the pneumatic 5 at the left of the box from opening, if anything, forcing it to collapse at a slight degree against the movement of the sheet opening the valve 8 on said pneumatic, admitting atmosphere into the pneumatic 5 and pneumatic 32 and allowing the pneumatic 32 on the right side of the box to bring the sheet to its central position, and vice versa, and thereby practically not allowing the sheet to wander from its path enough to be noticeable by the naked eye, as the valves operated by the edge guides on each side of the music sheet are kept in the closest relation, no matter what width sheet is employed.

Modifications in details may be resorted to without departing from the spirit of the invention or sacrificing any of its advantages.

What is claimed as new is:—

1. A pneumatic provided with a port open to the atmosphere and a valve for said port carried directly on and movable with said pneumatic and actuated from a note sheet. 90
2. A pneumatic having a port in its movable member and a valve carried by said movable member and actuated from a note sheet. 95
3. A pneumatic provided with a port in its movable member, and a valve carried by the movable member and controlled by a note sheet and movably mounted to control said port. 100
4. A pneumatic provided with a port in its movable member, and a movably mounted valve carried by said movable member to control said port, and means actuated from a note sheet to control said valve. 105
5. A pneumatic provided with a port in its movable member, a valve carried by said movable member to control said port, and a spool-moving pneumatic operatively connected with the first-named pneumatic. 110
6. A pneumatic provided with a port in its movable member, a valve mounted on said movable member and controlling said port, and a pneumatic arranged to move a music spool and operatively connected with the first-named pneumatic, said valve being controlled by a note sheet. 115
7. Pneumatically-controlled edge-engaging means embodying a pneumatic having a port open to the atmosphere and a valve mounted on and movable with the pneumatic and actuated from a note-sheet. 120
8. Pneumatic centralizing mechanism, and movably-mounted ported means, port-controlling means thereon and controlling the port thereof, edge-engaging means actuated from a note sheet and adapted to control the 130

- movement of the centralizing means both to the right and left. 65
9. Pneumatic sheet-registration means, embodying means to engage the edge of a note-sheet, a pneumatic having a port open to the atmosphere, and a valve for said port mounted on and movable with the pneumatic and controlled by the edge-engaging means. 70
10. 10. Pneumatic centralizing means, movable pneumatically-controlled means at opposite edges of and operated by a note sheet, and means whereby the former is controlled by the latter. 75
15. 11. A pair of pneumatics, means connecting them to move in unison, sheet-controlled means movable with said pneumatics, and valves mounted on said pneumatics and co-operating with said sheet controlled means. 80
20. 12. A pair of pneumatics one at each end of a music box, means connecting them to move in unison, sheet-controlled means movable with the pneumatics, and valves mounted on the pneumatics and co-operating with said sheet controlled means. 85
25. 13. A pair of pneumatics one near each end of a trackerbar, means connecting them to move in unison, and sheet-controlled means movable and in contact with the pneumatics. 90
30. 14. Pneumatically-actuated directly valve-controlled sheet moving means controlled by atmospheric air and coöperable with note sheets of varying widths. 95
35. 15. A pneumatic having a port open to the atmosphere and a valve movable with the pneumatic to control said port and maintained in close relation thereto regardless of the width of the note sheet. 100
40. 16. Movably mounted ported means, port-controlling means carried thereby, and sheet-controlled means for controlling said port controlling means. 105
45. 17. Movably-mounted ported means, port-controlling means movable therewith, and means for holding said port controlling means in close relation to the ports regardless of the width of a note sheet. 110
50. 18. Movably-mounted ported means, and valves secured thereto and said valves being controlled by a note sheet and the valves and ports automatically held in close relation to each other. 115
55. 19. Movably-mounted ported means, and valves secured thereto, said valves being controlled by a note sheet and the valves and ports held in close relation with each other when sheets of different widths are employed. 120
60. 20. Movably-mounted ported means and valves secured thereto, said valves being controlled by a note sheet and said valves and ports automatically held in close relation to each other when sheets of different widths are employed. 125
21. Movably-mounted ported means, and valves secured thereto, said valves being controlled by a note sheet and the valves and ports held in the same close relation when sheets of different widths are employed. 70
22. Movably-mounted ported means and valves secured thereto, said valves being controlled by a note sheet and said valves and ports automatically held in the same close relation to each other when sheets of different widths are employed. 75
23. A centralizing mechanism, movably-mounted ported means and valves secured thereto, said valves being controlled by a note sheet and the valves and ports being held in close relation to each other. 80
24. A centralizing mechanism, movably-mounted ported means and valves movable therewith, said valves and ports held in the same close relation to each other when sheets of different widths are employed. 85
25. A centralizing mechanism, movably-mounted ported means, and valves movable therewith, said valves and ports being held automatically in the same close relation to each other regardless of the width of sheet employed. 90
26. A pneumatic having a port open to the atmosphere, a valve mounted directly upon and movable with the pneumatic and actuated from a note sheet to control said port, and means for automatically keeping the valve and port in close relation regardless of the width of sheet employed. 95
27. A pneumatic centralizing mechanism, a pneumatic with a port, a valve on the pneumatic and movable therewith for controlling said port, and sheet coöperating means coöperable with said valve. 100
28. A pneumatic centralizing mechanism, a pneumatic with a port open to the atmosphere, a valve on the pneumatic actuated from a note sheet and controlling the port and means coöperating with said port and valve for keeping the same in the same close relation when sheets of different widths are employed. 105
29. A pneumatic with a port open to the atmosphere, a valve for said port mounted directly on and movable with the pneumatic and actuated from a note-sheet, and sheet-engaging means movable independently of the pneumatic and coöperating therewith, said valve and port being kept in close relation regardless of the width of the sheet employed. 115
- In testimony whereof I affix my signature.

GEORGE P. BRAND.
